(57) **CLAIM**

We claim the ornamental design for a spinal rod connector, as shown and described.

DESCRIPTION

FIG. 1 is a front, right perspective view of a spinal rod connector showing our new design;

FIG. 2 is a front view thereof;

FIG. 3 is a top view thereof;

FIG. 4 is a section view thereof taken along the line 4-4 in FIG. 3; and,

FIG. 5 is a section view thereof taken along the line 5-5 in FIG. 3.

The ornamental design which is claimed is shown in solid lines in the drawings. The broken lines in the drawings form no part of the claimed design. Broken lines formed by equal length dashes show unclaimed subject matter.
